Frederick K. Harker

UNITED STATES PATENT OFFICE

GEORGE A. PRITCHARD, OF ATLANTIC BEACH, FLORIDA

ADJUSTABLE VISOR

Application filed July 16, 1929, Serial No. 378,600. Renewed September 19, 1931.

This invention relates to two-part visors for use with the windows of motor cars, and my improvements are directed to means for adjusting the length of these devices in order that they may be thereby enabled to fit within window frames of varying widths, my invention also including means whereby the two parts of these adjustable visors will be held united in the lengthwise positions to 10 which they are adjusted.

In my earlier application, Serial No. 208,456, now Patent 1,745,866, filed July 26, 1927, I have described a visor that may be sprung into engaged position in the grooves 15 of a window frame, but in that instance the length of the visor had to be suited to the width of the window sash, thus requiring its production in a variety of different lengths, while the purpose of the present application, 20 which is a continuation in part of my application Serial No. 286,619, is to permit my improved visor to fit all widths of window frames.

Other features and advantages of my invention will hereinafter appear.

In the drawings:

Fig. 1 is a perspective of the front window of a motor car showing the visor in position.

Fig. 2 is a section taken on line 2—2 of 30 Fig. 1.

Fig. 3 is a section taken on line 3—3 of Fig. 1.

Fig. 4 is a perspective of one end of my visor, as it appears from the inside.

In the form of my invention herein illustrated let 1 indicate a motor car, having the window frame 2, with side runways 3 and top groove 4 for the slideable windows 5, said runways and groove having the usual felt lining 6.

My improved visor, which is adapted to engage within the runways and groove of the window frame, is in the present instance composed of two parts, respectively indicated by the reference numerals 7 and 8, which are, respectively, thin strips of sheet material, adapted to lie one against the other. Each strip is provided with an angled upper portion or flange adapted to engage within groove 4, between the felt and the

forward surface of the groove, said flanges respectively being indicated at 7a, 8a; also said strips are provided, at their outer ends, respectively with the side walls 7b and 8b, and said side walls respectively have the 55 angularly extended flanges 7c, 8c that are adapted to engage the opposite runways 3 of the window frame, between the felt 6 and the forward surfaces of said runways.

The bottom portions of strips 7, 8 are 60 turned and folded upwardly at the rear thereof, as indicated respectively at 7d, 8d. In the instance of the fold 7d upon part 7 it will be noted that this fold is pressed closely against the rear surface of said part 7 to thereby produce no more than a double thickness of material along the lower portion of said part 7. The part 8 is also provided with a rearwardly and upwardly turned fold, indicated at 8d, but this latter fold is not pressed against the rear surface of part 8, instead being disposed in spaced parallelism therewith, to form a trough or channel that snugly receives and frictionally retains the folded portion of part 7. The parts 7 and 8 may be of 70 equal length and their combined length, when interfitted, in excess of the maximum width to be found between the opposed side grooves in the window frames of motor cars. Hence in the manufacture of my adjustable visors 75 the parts 7 and 8 can respectively be made all of one size. This being the case it follows that in adapting a pair of parts 7 and 8 to provide a visor for use in a window of any width it is only necessary to interfit the folded portions of said parts so that they jointly provide a complete visor of the required length.

It must be understood that when the parts 7 and 8 are interfitted in the manner set forth the frictional engagement between the portions 7d, 8d is so secure that lengthwise slidable motion between said parts is not practicable and in fact the only way in which said parts can be connected is by driving 90 them together vertically. The parts 7 and 8 can be put together by hand in this manner, but it is more difficult to disengage them with only manual means. However it is unnecessary to disengage the parts 7, 8 once 95 100

they have been connected and thus produce a complete visor, because the main object of my invention is to economize in the manufacture by making the parts in one standard size, thereby avoiding the use of a large number of dies, now required in the production of visors in a great variety of sizes; and, furthermore enabling the dealer to furnish the same sized parts to fit the windows of 10 all makes of cars.

Tight as is the frictional union between the parts 7, 8 in the interfitted relation thereof, such union is not in itself sufficient to keep the two part visor in fixed, non-vibrational relation in the grooves of a window frame into which such visor has been sprung. It is, I have found, necessary to produce a tensional arch in the visor in order to sufficiently increase the frictional effect between 15 the parts 7 and 8 for this purpose. Therefore, in gauging the combined length of the parts 7, 8 with respect to a given window frame I cause the length of the bi-part visor to exceed the width of the window frame, so 20 that when the visor has been sprung to permit flanges 7a, 8a to enter the window grooves, the visor will not straighten out but will instead have an arched effect that rigidly and immovably connects the interfitted 25 portions of parts 7, 8.

Thus, with the two parts of the visor interfitting and interengaged at their folded portions 7d, 8d, and with the visor length exceeding the width between the opposed grooves at 30 the window sides, said visor being of spring-like material and assuming an outwardly bowed or arch-like effect when sprung with its flanges 7c, 8c engaging said grooves, thereby the visor parts become so securely bound 35 together and fixed in their service position in the window frame that no amount of vibration set up in the travel of the motor car at high speed over rough roads will dislodge the visor or cause its parts either to shift or to 40 rattle.

Variations within the spirit and scope of my invention are equally comprehended by the foregoing disclosure.

I claim:—

50 A visor for motor car windows comprising two parts of sheet material, an end portion of one part overlapping an end portion of the other part, one part having a rearwardly turned fold at its lower portion that 55 is pressed closely against the rear surface of said part to constitute a male member, and the other part having a rearwardly turned fold at its lower portion spaced from its rear surface to constitute a channel-like female 60 member capable of snugly receiving said male member in frictional, interfitted relation, said parts respectively being adapted at their outer ends to engage the opposite grooves in a window frame, the length of said two part 65 visor exceeding the width between the op-

posed window grooves, whereby said visor when sprung into engagement with said grooves has an arched effect that binds the parts together in non-slidable relation and tensionally connects them to the frame.

70 Executed this 13th day of July, 1929.
GEORGE A. PRITCHARD.
